(57) **CLAIM**

An ornamental design for a scooter, as shown and described.

DESCRIPTION

FIG. 1 is a top left perspective view of a scooter in accordance with one embodiment of the present invention; FIG. 2 is a top right perspective view of the scooter of FIG. 1;

FIG. 3 is a bottom right perspective view of the scooter of FIG. 1;

FIG. 4 is a front elevational view of the scooter of FIG. 1; FIG. 5 is a rear elevational view of the scooter of FIG. 1; FIG. 6 is a left side elevational view of the scooter of FIG. 1;

FIG. 7 is a right side elevational view of the scooter of FIG. 1;

FIG. 8 is a top planar view of the scooter of FIG. 1; FIG. 9 is a bottom planar view of the scooter of FIG. 1;

FIG. 10 is a top left perspective view of a scooter in accordance with another embodiment of the present invention; FIG. 11 is a top right perspective view of the scooter of FIG. 10;

FIG. 12 is a bottom right perspective view of the scooter of FIG. 10; FIG. 13 is a front elevational view of the scooter of FIG. 10; FIG. 14 is a rear elevational view of the scooter of FIG. 10; FIG. 15 is a left side elevational view of the scooter of FIG. 10;

FIG. 16 is a right side elevational view of the scooter of FIG. 10; FIG. 17 is a top planar view of the scooter of FIG. 10; and, FIG. 18 is a bottom planar view of the scooter of FIG. 10. The elements shown in dot-dot-dot phantom are for illustrative purposes only and do not form part of the claimed design.

1 Claim, 18 Drawing Sheets
